UNITED STATES PATENT OFFICE.

SAMUEL M. DOWST, OF CHICAGO, ILLINOIS.

DESIGN FOR A GAME-BOARD.

46,163.

Specification for Design.

Patented July 28, 1914.

Application filed May 22, 1914. Serial No. 840,384. Term of patent 14 years.

To all whom it may concern:

Be it known that I, SAMUEL M. Dowst, a citizen of the United States, residing at Chicago, in the county of Cook and State of Illinois, have invented a new, original, and ornamental Design for a Game-Board, of which the following is a full, clear, and exact description, reference being had to the accompanying drawing, forming a part hereof.

My invention relates to a design for a game-board which embodies a plan for golf course that is very pleasing and attractive in appearance.

In view of the size of the practicable game-board, and the reduced proportions of the same in the accompanying drawings, it was necessary to illustrate the same in two figures.

In the drawings: Figure 1 shows a plan of the upper portion of a game-board embodying my new design. Fig. 2 is a plan of

the lower portion of the same embodying my new design.

Referring to the drawings, it will be seen that my design consists of a diagrammatical view of a very picturesque nine hole golf course which shows a club-house in the center thereof and the teeing platform, the fair-greens and putting-greens of the golf links arranged in convenient order around the same, together with artificial hazards, and scenic and topographical features in connection therewith.

I claim—

The ornamental design for a game-board, as described and shown.

In witness whereof, I have hereunto set my hand this 14th day of May, 1914.

SAMUEL M. DOWST.

Witnesses:

JOHN C. HALLENBECK,
FRANK D. THOMASON.
